THERMOSTATIC CIRCUIT CLOSER

Olaf A. Sahlbom, Everett, Wash.

Application January 4, 1938, Serial No. 183,371

1 Claim. (Cl. 200—141)

This invention relates to a thermostatic circuit closer, the general object of the invention being to provide a container having mercury therein, with means for closing a circuit when the mercury rises in the container to a certain position therein.

This invention also consists in certain other features of construction and in the combination and arrangement of several parts, to be herein-
19 after fully described, illustrated in the accompanying drawing and specifically pointed out in the appended claim.

In describing the invention in detail, reference will be had to the accompanying drawing where-
15 in like characters denote like or corresponding parts throughout the several views, and in which:

Figure 1 is a front view of the device.

Figure 2 is a longitudinal sectional view
20 through the body of the device.

Figure 3 is a view of the plug of non-conductive material, with the plug in inverted position.

Figure 4 is a section on the line 4—4 of Figure 2.

25 Figure 5 is a section on the line 5—5 of Figure 2.

In these views the numeral 1 indicates a plug or body of non-conductive material and having a bore 2 therein, the lower end of which is en-
30 larged as shown at 3 and the upper end of the bore terminates an appreciable distance from the upper end of the plug and a transverse hole 6 in the plug communicates with the said upper end of the bore and the outer ends of the hole con-
35 nect with the grooves 7 in the sides of the plug, said grooves extending from the hole through the upper end of the plug. A lower metal cap 8 fits over the lower part of the plug and an upper metal cap 9 fits over the upper portion thereof. The lower end of the lower cap 8 is spaced from the lower end of the plug and forms a chamber for receiving mercury and when this mercury ex-

pands under the action of heat, produced by a fire for instance, it will pass up the bore 2 and then flow through the hole 4 into the grooves 7. Thus the mercury will contact the upper cap and electrically connect the caps together, thus completing the circuit, portions of which are connected with the lower clamp member 10 and another portion with the upper clamp member 11, the clamp members being carried by the block 12 of non-conductive material and said clamp mem-
10 bers engaging the ends of the device as shown in Figure 1.

By adjusting the lower cap 8 the level of mer-
cury therein can be adjusted whereby the device
can be adjusted to operate at any desired tem-
perature.

It is thought from the foregoing description
that the advantages and novel features of the in-
vention will be readily apparent.

It is to be understood that changes may be
made in the construction and in the combination
and arrangement of the several parts, provided
that such changes fall within the scope of the
 appended claim.

Having described the invention what is claimed
as new is:

A device of the class described comprising a
plug of non-conductive material and having a
bore therein extending from a point spaced from
its upper end through the lower end, said lower
end of the bore being enlarged and said plug hav-
ing a transverse hole therein which communi-
cates with the upper end of the bore and said plug
having grooves in its sides which extend from
the hole through the upper end of the plug, a low-
er cap of conducting material having a sliding fit
on the lower part of the plug, and containing
mercury and an upper cap of conducting mate-
rial enclosing the upper portion of the plug, the
adjacent ends of the caps being spaced apart.

OLAF A. SAHLBOM.
